UNITED STATES PATENT OFFICE.

MAXIME DE GOMBERT, OF PARIS, FRANCE, ASSIGNOR TO THE COMPAGNIE GÉNÉRALE DE TEINTURERIE ET APPRETS, (SYSTEME, ANDRÉ LYON,) OF SAME PLACE.

MACHINE FOR DRESSING SILK AND OTHER FABRICS.

SPECIFICATION forming part of Letters Patent No. 269,188, dated December 19, 1882.

Application filed May 26, 1882. (No model.)

To all whom it may concern:

Be it known that I, MAXIME DE GOMBERT, of Paris, France, have invented an Improved Machine for Dressing Silk and other Fabrics; 5 and I do hereby declare that the following is a full, clear, and exact description of the same, reference being had to the annexed drawings, making a part of the same.

This invention relates to machines for dressing or stiffening silk or other fabrics.

The invention consists of a trough of copper or other suitable material to contain the size or other liquid with which the fabric is to be dressed, in combination with a frame and 15 with a rotating winder, arranged and operated as hereinafter described.

The invention is illustrated, by way of example, in the accompanying drawings, in which Figure 1 represents a sectional side elevation 20 of my improved machine; Fig. 2, a sectional end view, and Fig. 3 a plan, of the said machine. Fig. 4 shows part of the trough and one loose roller in section, to illustrate how the fabric is placed when being passed a first 25 time through the machine. Fig. 5 is a cross-section through the rollers of the winding mechanism to show the method of engaging the fabric on the winding device; and Fig. 6 is a section through the same rollers to illustrate their position when the fabric is to be removed from the winder.

The same letters of reference indicate the same parts in all the figures.

a is a trough or trough-like vessel, made of 35 metal or other substance, and supported on a suitable stationary frame. *b* is a roller hung in the said frame above one end of said trough *a*. *c c* are rollers hung in the lower part of said trough at a distance from roller *b*, all 40 parallel therewith. *d d* are two rollers hung in arms *e e*, which are mounted on trunnions that hang in the said supporting frame. Caps *f* hold the rollers *d* in their bearings, and are fastened down by screws *g*. The trunnions 45 outside of their bearings in the supporting frame have placed upon them wheels *h h*, which gear with similar wheels (also marked *h h*) on

a shaft, *l*, that carries a crank-handle, *i*, all as clearly shown in the drawings.

The following is the operation of the machine: The fabric is first placed in folds at the rear end of trough *a*, as in Fig. 4, below the roller *b*; thence it passes over the loose roller *b* and around the series of rollers *c*, which guide it in its passage through the trough. On leaving these rollers the fabric is led upward to the rollers *d d*, which rollers are carried by the arms *e e*. The fabric is passed around the upper rollers *d*, and its end *h* brought down so as to be nipped against 50 the lower roller *d*, as in Fig. 5. When the shaft *l* is now revolved the length of fabric is drawn through the dressing in the trough, being held in the size by the rollers *c c*, and wound around the rollers *d d*. The fabric can then be transferred to another machine to undergo a similar treatment; or it may be passed a second time through the same machine, in which case, however, the fabric is not placed in the same 55 position in the trough as before, for in this case the two rollers *d* are first brought into a horizontal plane, as in Figs. 2 and 3, and the caps *f* of arms *e* are raised by releasing the locking-screws *g* to allow of the rollers *d d* being lifted out with the fabric wound thereon. 60 The rollers are then held in the position Fig. 6 by an attendant, and the roller *b* is passed through the roll of fabric, and afterward, with the fabric thereon, dropped into its bearings. The two rollers *d d* are then replaced in their 65 bearings. The free end of the fabric is then nipped by said rollers *d* as before, and the operation repeated. The fabric when it leaves the rollers is in form of a flattened tube, and may then be put in a wrapper for conveyance 70 to the drying-machine.

The form and arrangement of the various parts of the machine may be varied without departing from the invention.

While the machine is in operation the fabric will be held stretched by the revolving rollers *d d* and rollers *c* and *b*, so as to be thoroughly exposed at all its parts to contact with the contents of the vessel *a*. The result will

be a fabric sized more thoroughly than when exposed in folds or slack to the contents of the vessel *a*.

I claim—

5 The combination of the trough *a* with the rollers *b* and *c* and with the rollers *d*, arms *e*, having trunnions, and with mechanism, sub-

stantially as described, for revolving the arms *e*, as set forth.

MAXIME DE GOMBERT.
